(57) **CLAIM**

The ornamental design for a round mirror with frame as shown and described.

DESCRIPTION

FIG. 1 is a perspective view of the round mirror with frame according to a first embodiment;

FIG. 2 illustrates a close-up view of the area labeled in FIG. 1;

FIG. 3 illustrates a front view corresponding to FIG. 1;

FIG. 4 is a front view of the round mirror with frame according to a second embodiment;

FIG. 5 illustrates a close-up view of the area labeled 5 shown in FIG. 4;

FIG. 6 illustrates a left side view corresponding to FIGS. 1, 3, 4, and 8, a right side view is identical;

FIG. 7 illustrates a top view corresponding to FIGS. 1, 3, 4, and 8, a bottom view is identical; and,

FIG. 8 is a perspective view of the round mirror with frame according to the second embodiment.

The broken lines in the drawings depict portions of the round mirror with frame that form no part of the claimed design. The dot-dash broken lines shown in FIGS. 1-2 and 4-5 are for the purpose of annotating the enlargements only and form no part of the claimed design.
